UNITED STATES PATENT OFFICE.

JOHN D. THOMPSON, OF TORONTO, ONTARIO, CANADA.

TOOL-HANDLE.

968,815.

Specification of Letters Patent. Patented Aug. 30, 1910.

Application filed April 21, 1910. Serial No. 556,677.

To all whom it may concern:

Be it known that I, JOHN D. THOMPSON, a subject of the King of Great Britain, residing at Toronto, county of York, Province 5 of Ontario, Canada, have invented a certain new and useful Improvement in Tool-Handles, and declare the following to be a full, clear, and exact description of the same, such as will enable others skilled in the art to 10 which it pertains to make and use the same, reference being had to the accompanying drawings, which form a part of this specification.

This invention relates to tool handles.

15 It has for its special object a handle adapted to be used with engraving tools.

In the drawings:—Figure 1, is a side elevation of the handle, and a line graver held therein. Fig. 2, is a reverse plan view of 20 the tool-holding part of the handle. Fig. 3, is a side elevation of the several parts. Fig. 4, is a side elevation of the handle with the burnishing tool held therein. Fig. 5, is a reverse plan view of the tool with the bur- 25 nisher held therein. Fig. 6, is a side elevation of the burnisher. Fig. 7, is an end elevation of the handle head.

The handle consists of the holding part 1 of wood or similar material, in which there 30 is inserted a shank 2 which terminates at its front end with an engaging member 3 serrated on that side which is normally held downward and provided on the side opposite the serrations with a screw abutting face 35 4; a projection 5 extends therefrom that is adapted to engage in the socket 6 of the tool. On the member 3 is pivotally supported a clamp comprising a split ring 6, the lips 7 of which along the slot extend 40 under the serrations 8 of the member 3. The projection or nose 5 extends beyond the clamp 6 and the clamp is capable of a slight oscillating motion on its pivot 9. The tool is provided with flanges 10 that project 45 from a web; the web engages in the slot between the lips 7 and the flanges engage between the lips and the serrated face. The tool may be provided with serrations 11 to engage in the serrations 8, or it may be left 50 plain and provided with a socket 6 within which the nose 5 engages. Across the clamp underneath the serrations 8 in the assembled tool a pin 12 crosses from side to side of the clamp and the ends are riveted over, making 55 the pin a permanent fixture with respect to the clamp; this pin is spaced from the

lower surface of the member 3 to permit the insertion under the pin and between the pin and the face of a tail prong 13 on some of the tools. A tool G, which is a line 60 graver, may be inserted in the handle with either end foremost. As shown in Fig. 1, it is properly inserted for draw-line engraving; inserted with the inclined end foremost it is properly located for sharpening 65 purposes or for push-line engraving, although a push-line engraver is not commonly used. The tool B is inserted with the tail 13 under the pin or rivet 12, and with the nose 5 of the member 3 engaging in the socket 70 6^a, and the clamp is then drawn tightly against the flanges 11^a of the tool B by means of a thumb screw 14, and the tool is very firmly and securely held in place.

What I claim is:—

1. A handle for gravers' tools, having in 75 combination a tang terminated at its front end with a member provided with a serrated face, and with a smooth bearing face opposite the serrated face, a split clamp pivotally connected to said tang and provided with overhanging lips extending under said serrated face, a thumb screw engaging through a wall of the clamp against the engaging portion of the tang, substantially as de- 80 85 scribed.

2. In a handle for gravers' tools, having in combination a tang, a serrated projection extending from the tang, a nose terminating the serrated portion, a split clamp pivotally 90 connected to the tang provided with overhanging engaging lips and with a thumb screw and a pin engaging across the split clamp, substantially as described.

3. A handle for gravers' tools, having in 95 combination a tang terminated at its front end with a member provided with a tool-engaging face and with a bearing face opposite the tool-engaging face, a split clamp pivotally connected to said tang provided 100 with edges extending along the slit and which overhang the tool-engaging face, a thumb screw engaging through a wall of said split clamp and against the bearing face opposite the tool-engaging face, sub- 105 stantially as described.

4. In a handle for gravers' tools, a combination of a tang, a projection extending from the tang and provided with a nose attached to engage a socket in the tool, a split 110 clamp pivotally connected to the tang provided with edges extending along the split

which overhang the tool-engaging face of the projection, a pin engaging across the split clamp at the rear of the split portion thereof, substantially as described.

- 5 5. A handle for gravers' tools, having in combination a tang terminated at its front with a member provided with a tool-engaging face, a bearing face opposite the tool-engaging face, a split clamp terminal connected to said tang and provided with edges which overhang the tool-engaging face of

15 said tang, a thumb screw engaging through a wall of the clamp against the bearing portion of the tang, substantially as described.

In testimony whereof, I sign this specification in the presence of two witnesses.

JOHN D. THOMPSON.
